UNITED STATES PATENT OFFICE.

WESLEY EDWIN SPAFFORD, OF TORONTO, ONTARIO, CANADA.

HORSESHOE.

No. 899,631.

Specification of Letters Patent. Patented Sept. 29, 1908.

Application filed April 10, 1908. Serial No. 426,390.

To all whom it may concern:

Be it known that I, WESLEY EDWIN SPAFFORD, of the city of Toronto, in the county of York, in the Province of Ontario, Canada, 5 have invented certain new and useful Improvements in Horseshoes, of which the following is the specification.

My invention relates to improvements in horse shoes, and the object of the invention 10 is to devise a simple, convenient, strong and durable shoe in which the sharp calks may be readily removed when it is desired to have the horse travel on a smooth shoe and readily replaced again when desired without having 15 to remove the shoe and in a minimum period of time.

The invention includes the novel features of construction and arrangement of parts hereinafter described and particularly set 20 forth in the appended claim.

A horse shoe constructed in accordance with my invention is illustrated in the accompanying drawings in which,

Figure 1, is a perspective view of a shoe in 25 the reverse position with my attachment connected thereto. Fig. 2, is a perspective view of the attachment with the clamping screw removed. Fig. 3 is a perspective view of the toe clip. Fig. 4 is a perspective 30 view of a detail of one of the side pieces. Fig. 5 is a perspective view of the turning screw. Fig. 6 is a central longitudinal sectional view from front to rear of the shoe. Fig. 7 is a cross section of the shoe taken through the 35 clamping screw.

In the drawings like letters of reference indicate corresponding parts in each figure.

A is the smooth shoe provided with the usual flat heel calks.

40 B is a central toe clip, which is designed to straddle the toe of the shoe horizontally, the said toe clip having as indicated in Fig. 3, the arc-shaped overhanging piece B' provided with end bosses or enlargements B² 45 having holes 1, the reversely turned depending arc-shaped portion B³ designed to fit the inside of the shoe at the toe and provided with lugs B⁴ to fit on top of the shoe and shown lowermost in the drawing on account of the 50 piece being inverted.

C and C' are the side pieces, which are substantially arc-shaped in form or more properly conform to the shape of the shoe and are provided with end holes 2 designed 55 to register with the holes 1 in the toe clip when said ends of the side pieces are fitted

under the holes in the toe clip as indicated in Figs. 1 and 2. In this position the calks 3 are provided with flat flaring ends 3' as indicated by dotted lines in Fig. 6, which 60 calks extend through the holes 2 and 1.

4 are the end heel calks, which extend through holes 4', the calks being provided with flat flaring heads, which abut the horse shoe proper as indicated in dotted lines in 65 Fig. 6. The piece C is provided with a square socket C² formed in the projection C³, the portion C⁴ of which extends on the upper side of the shoe. The piece C' is provided with a projection C⁵ having a round socket 70 C⁶ the portion C⁷ of the projection extending above the shoe.

In Fig. 7, the shoe is shown in the inverted position and I have referred particularly to this figure in describing the above construction. 75

The socket C² is a tapered socket and into such socket fits the tapered head D' of the screw D. D² is a screw socket, which in Fig. 7 I show partly broken away and in section. 80 The screw socket D² is provided with a round tapered head D³, which fits in the round socket C⁶.

To place and secure the pieces C C' and B in position the piece or toe clip B is inserted 85 as indicated in Fig. 6, so as to extend above and below the shoe, the calks 3 being held in place by abutting the shoe. The pieces C and C' are spread out over the sides of the shoe and the connecting turn screw is fitted 90 with a square tapered end D' in the square socket C² and the round tapered end D³ in the round socket C⁶ and the sided portion of the socket D² is turned by a wrench until the two side pieces are spread sufficiently far apart, 95 so as to force the projections C³ and C⁵ to straddle the shoe and securely hold the pieces C and C' and B in position. The shoe A, of course, is fitted on to the foot primarily and the attachments B C C' hereinbefore described it will be readily seen can be not only 100 attached but quite as easily detached by following the reverse operation to that immediately above described.

Such an attachment to horse shoes as that 105 described is very simple, cheap and efficient and convenient dispensing with reshoeing a horse for icy or slippery weather.

What I claim as my invention is:

1. In a horse shoe, the combination with 110 the toe piece having the arc-shaped upper portion and lower projections and intermedi-

ate connection adapted to fit the inside of the toe portion of the shoe, of the side pieces adapted to fit on to the sides of the shoe and having the ends extending underneath the 5 ends of the toe clip and the toe calks extending through holes in such ends and abutting the shoe, and the heel calks extending through the heel ends of the pieces and abutting the shoe and means for fastening the toe 10 clip and side pieces in position as and for the purpose specified.

2. In a horse shoe, the combination with the toe piece having the arc-shaped upper portion and lower projections and intermediate 15 connection attached to fit the inside of the toe portion of the shoe, of the side pieces adapted to fit on to the sides of the shoe and having the ends extending underneath the

ends of the toe clip and the toe calks extending through holes in such ends and abutting 20 the shoe, and the heel calks extending through the heel ends of the pieces and abutting the shoe, projections formed on the side pieces and extending above the shoe, a square tapered socket formed on one projection, 25 a round tapered socket formed on the opposite projection, a square tapered headed bolt extending into the square socket, an internally threaded socket designed to fit on to the bolt and provided with a round tapered 30 head as and for the purpose specified.

WESLEY EDWIN SPAFFORD.
